UNITED STATES PATENT OFFICE.

GEORGE M. CÔTÉ, OF PITTSBURG, PENNSYLVANIA, ASSIGNOR TO STANDARD STEEL TIE COMPANY, OF PITTSBURG, PENNSYLVANIA, A CORPORATION OF DELAWARE.

RAILWAY-TIE.

No. 890,557.

Specification of Letters Patent.

Patented June 9, 1908.

Application filed November 23, 1907. Serial No. 403,490.

To all whom it may concern:

Be it known that I, GEORGE M. CÔTÉ, a citizen of the United States, and residing in the city of Pittsburg, in the county of Allegheny and State of Pennsylvania, have invented or discovered new and useful Improvements in Railway-Ties, of which the following is a specification.

My invention consists in new and useful 10 improvements in metal railway ties.

My process of manufacturing the same consists in taking a sheet or plate of metal of proper size, bending the same up into substantially box form and forming circumferentially thereof a plurality of corrugations. I prefer to locate one of said circumferential corrugations at either side of the rail platform as illustrated in the drawings. Openings, as hereafter more fully described, are 20 provided in the top of the tie for the adjustment of the rail fasteners. If desired, I may obtain the circumferential corrugations above referred to by first forming the same as transverse corrugations in the flat sheet 25 which become circumferential corrugations when the sheet is bent up into box form.

In the accompanying drawings, Figure 1 is a broken perspective of the original sheet or blank; Fig. 2 is a broken perspective of the 30 completed tie; Fig. 3 is a partial longitudinal section of the tie showing the rail secured in place, and Fig. 4 is a broken perspective of a modified form of the plate, the corrugations being formed therein before bending up into 35 box form.

The following is a detailed description of my metal tie as the same is illustrated in the drawings.

I provide a rolled or otherwise formed 40 metal sheet 1 (Fig. 1) which is bent along the dotted lines *a—a* into a box form as shown in Fig. 2, the sides of the box being preferably tapered as shown and the two portions 2—2 which form the bottom of the box being 45 preferably slightly spaced apart to form the slot 3. By this means I provide a spring metal tie adapted to assume the wave motion caused by traffic without fracture and without pounding the ballast. In the same 50 operation by which the sheet 1 is bent up into the box form shown in Fig. 2 I form the circumferential corrugations 4—4, preferably located one on each side of the rail platform 5. The corrugations serve to stiffen 55 the tie against any flattening tendency and

also form a reinforced bearing for the fastening devices to be described.

The rail platforms 5—5 are provided with openings 6—6 extending preferably from corrugation to corrugation 4—4 and somewhat to the rear of each corrugation 4 is a bolt hole 7.

8 is the rail which rests on the rail platform 5 and 9—9 are fasteners whose upper portions engage the base, web and ball of the 65 rail 8. The lower portions of the fasteners 9—9 which extend through the aperture 6 are preferably substantially Z shaped whose arms 10—10 extend away from the rail platform. Adjacent to the extremities of arms 70 10—10 are longitudinally slotted holes 11—11 which are located beneath the holes 7—7 in the tie top.

12—12 are bolts up through the holes 11—11 and 7—7 and held in place by nuts 75 13—13 screwed down on the tie top.

14—14 are spring locking plates through which bolts 12—12 pass and whose tongue 15 prevents the nuts 13—13 unscrewing.

The heads of the bolts 12—12 are rounded 80 where they bear upon the under face of arms 10—10 so that a certain amount of play is permitted between the bolt and the fastener to assume the jar and thrust of traffic on the rails. The bolts 12—12 fit loosely in holes 85 7—7 so as to be rocked slightly without danger of fracture or being sheared off. I prefer to outwardly and downwardly incline the upper parts of arms 10—10 so as to prevent contact between the under side of the 90 tie top and the fastener thus transmitting the full upward tension of the bolt into pressure of the fastener against the rail. The apertures 6—6 and 7—7 are preferably stamped out of the sheet 1 during the process 95 of bending the same up into box form.

If desired I may first form the corrugations 4—4 in the sheet 1 (see Fig. 4) before the same is bent up into box form which corrugations then become circumferential corrugations as shown in Fig. 2.

The tie made by this method is of very inexpensive manufacture. Moreover it, at the same time, possesses both strength enough to sustain the loads which are to be imposed 105 and elasticity enough to safely assume the vibration and wave motion of traffic.

What I desire to claim is:

1. As an article of manufacture, a railway tie consisting of a metal plate bent up into 110

- substantially box form and circumferentially corrugated.
2. As an article of manufacture, a railway tie consisting of a metal plate bent up into substantially box form circumferentially corrugated and provided with apertures in the top thereof.
3. As an article of manufacture, a railway tie consisting of a metal plate bent up into substantially box form with a circumferential corrugation at either side of the rail platforms.
4. As an article of manufacture, a railway tie consisting of a metal plate bent up into substantially box form with a slotted bottom and having a circumferential corrugation at either side of the rail platforms.
5. As an article of manufacture, a railway tie consisting of a metal plate bent up into substantially box form with tapered sides 20 and having circumferential corrugations at either side of the rail platforms.
6. As an article of manufacture, a railway tie consisting of a metal plate bent up into substantially box form with tapered sides 25 and slotted bottom, and having circumferential corrugations at either side of the rail platform.

Signed at Pittsburg, Pa., this 22nd day of November, 1907.

GEORGE M. CÔTE.
